MECHANISM FOR IMPARTING FALSE TWIST
TO TEXTILE ROVINGS

Fernando Casablancas, Manchester, England, assignor to Casablancas High Draft Co., Ltd., Manchester, England, an English corporation

Application February 3, 1937, Serial No. 123,917
In Spain February 15, 1936

6 Claims. (Cl. 19—154)

This invention relates to false twist mechanisms employed in spinning or roving machines for imparting a false twist to the roving which is being spun or drawn.

5 The invention is especially applicable to mechanisms of this type in which the toothed wheels or pulleys which operate the individual twist tubes of the machine are, in their turn, driven by means of a transmission chain or belt, by 10 means of a series of toothed wheels mounted on a common shaft, or by other means which render it impossible to interrupt the rotation of the toothed wheel or pulley corresponding to one of the twist tubes without simultaneously interrupting the rotation of the toothed wheels or pulleys corresponding to all the other twist tubes of the 15 machine.

In these false twist mechanisms, in order to 20 adapt the dimensions of the mechanism to the distance between the spindles of the spinning machine, it is necessary to make both the driving wheels or pulleys and the twist tubes of relatively small diameter, which renders the operation of 25 passing the roving through the twist mechanism difficult, since the fingers cannot be inserted in the twist tube in order to pass the roving and it is necessary to use special tools or instruments for doing this.

The improvements forming the subject of the 30 present invention have for their chief object the provision of a false twist mechanism of the aforesaid type which is of extremely light and strong construction and in which the twist tube is used also as threading-in member for passing the roving through the twist mechanism.

A second object of the invention is to provide 35 a driving connection for effecting the rotation of the twist device when the latter is in position in the twist mechanism while allowing the said 40 twist device to be withdrawn readily from the mechanism when desired.

A further object is to provide such a driving 45 connection which is so constructed that, upon rotation of the twist tube being impeded, the said connection is automatically rendered inoperative thereby preventing damage to the apparatus and also facilitating the removal of the twist device.

Yet another object of the invention is the provision 50 of a false twist mechanism having a removable twist device wherein, upon the twist device with an end of the roving projecting therefrom being inserted into the mechanism, the end of the roving is automatically gripped by a pair

of drawing rollers or the like mounted adjacent the twist mechanism.

In order that the said invention may be clearly understood and readily carried into effect the same will now be more fully described with reference to the accompanying drawing in which:

Figure 1 is a cross-sectional view of the false twist mechanism shown in conjunction with an endless belt drawing mechanism,

Figure 2 is a detail in section through the driving wheel which surrounds the twist tube, and

Figure 3 is an exterior side view of the twist tube.

The mechanism illustrated in Figure 1 comprises a driving shaft 1 which extends over the 15 entire length of the machine and which carries, for each of the false twist mechanisms, a helical pinion 2, which drives a second helical toothed wheel 3, inside which is mounted the false twist tube 4. The pinions 2 are keyed on the spindle 20 1, so that when the machine is in operation the wheels 3 of the different twist mechanisms rotate continuously and the movement of one of them cannot be arrested without interrupting the rotation of the other wheels.

The false twist tube 4 feeds the roving to the 25 belts 5 of the drawing mechanism which belts are actuated by the cylinders 6 in the known manner.

In the construction illustrated in the drawing, 30 the hub 10 of the wheel 3 rotates within a bearing 7, which is secured to a frame 8 which is in turn supported by a bar 9 suitably mounted in the machine.

The twist tube 4 is of relatively small diameter 35 and is disposed inside the hub 10 of the wheel 3, and in order to ensure the transmission of the drive from the wheel 3 to the tube 4 there is provided between the two a driving connection 40 which, in the construction illustrated in the drawing, comprises a stop or projection 11 formed on the hub 10 and a corresponding projection 12 formed on the tube 4. Thus, the tube 4 is simply introduced inside the wheel 3 and upon its reaching the operative position illustrated in Figure 1, the stop 11 of the wheel engages the stop 12 of the tube 4 and thus drives the twist tube.

These stops are preferably so formed that their 50 side surfaces are bevelled as is shown in the drawing, the object being to ensure that, should for any reason the rotation of the tube 4 be impeded, the bevelled faces of the two stops 11 and 12 cause the tube 4 to be displaced axially towards the right of Figure 1 until the stops disen-

gage when the wheel 3 can continue to rotate without driving the tube 4.

This greatly facilitates the threading of the roving. To thread the roving it is sufficient to 5 grasp the projecting part 13 of the tube 4 by hand and to withdraw it from the wheel 3, whereupon the roving can be introduced into the tube 4, being passed through the longitudinal slot 14 in this tube, so that a short length of roving 10 extends through the end of the tube. The tube 4 with the roving is then simply reintroduced into the wheel 3. When the stops 11 and 12 come into contact the tube 4 is rotated by the wheel 3 and at the same time, since the tube extends very close to the belts 5, the length of roving 15 which extends beyond the tube is engaged by these belts and thus the mechanism is automatically threaded.

As will be understood, the driving connection 20 need not be formed by the two stops 11 and 12 precisely as illustrated in the drawing, but other arrangements may be adopted. For example one of the two parts, such as the wheel 3 may be formed with a recess or aperture for engagement 25 with the stop 12 of the other part. It would be preferable in this case also for the edges of the stop and of the recess or aperture to be bevelled so that if the movement of the tube 4 is impeded the mechanical connection between the two parts 30 may be broken by the sliding of the tube 4.

What I claim and desire to secure by Letters Patent of the United States is:

1. In mechanism for imparting false twist to textile rovings the combination of a rotatably mounted member formed with an axially extending aperture and with a recess formed with at 35 least one bevelled face, means for rotating the said member, and a false twist tube removably supported within the said member, said false twist tube being slotted along its length and formed with a projection which is adapted to enter into the said recess when the twist tube is in position within the rotatable member and to be engaged by the said bevelled face of said recess to transmit the rotation of the said member to the said twist tube said twist device being freely slidable longitudinally within the said rotatable member whereby upon rotation of the twist tube being 40 impeded said twist tube is caused to slide longitudinally under the action of the said bevelled face on the said projection to disengage said projection from the said recess to render inoperative the driving connection between the rotatable member and the twist tube.

2. In mechanism for imparting false twist to textile rovings the combination of a bearing member, a hollow sleeve member rotatably mounted within said bearing member and formed with a recess at one of its ends, means for rotating the 50 said sleeve member, and a false twist tube adapted to be introduced into said sleeve member, said twist tube being formed with a longitudinal slot to admit the introduction of the roving into the tube before the said tube is introduced into the sleeve member and being provided adjacent one of its ends with a flange and with a projection, said projection being adapted, when the 55 twist tube is introduced into the sleeve member until the said flange engages the end of the said sleeve member, to be engaged in said recess to transmit the rotation of the sleeve member to the twist tube, said recess and said projection each being formed with a pair of bevelled faces whereby upon rotation of the twist tube in either direction being impeded, said twist tube 60

is caused to slide longitudinally within said sleeve by the action of one of the bevelled faces of said recess on one of the bevelled faces of said projection to disengage said projection from said recess to render inoperative the driving connection between the rotatable member and the twist tube. 5

3. In mechanism for imparting false twist to textile rovings the combination of a member mounted for rotation about a generally horizontal axis and formed with an axially extending aperture and with a shoulder, means for rotating the said member, and a false twist device adapted to be inserted into the aperture in and to be supported by said member, said false twist device being slotted along its length and formed with a shoulder which is adapted, when the twist device is introduced to the maximum extent into the 10 rotatable member to be engaged by the said first-named shoulder to transmit the rotation of the 15 said member to the twist device, the arrangement being such that the twist device continues to be supported by the said rotatable member after having been retracted therein by an amount sufficient to disengage the said shoulders and 20 interrupt the driving connection therebetween. 25

4. In mechanism for imparting false twist to textile rovings the combination of a hollow sleeve member mounted for rotation about a generally horizontal axis, means for rotating the said 30 sleeve member, and a false twist member slotted along its length and adapted to be inserted into and to be supported by the sleeve member, one of said members being formed with a recess and the other of said members being formed with a projection adapted to enter into the said recess when the false twist member is fully introduced into the sleeve member, the arrangement being such that the sleeve member continues to support the false twist member after the latter has been withdrawn sufficiently to disengage the projection from the recess to interrupt the driving connection between the two members. 35 40

5. In mechanism for imparting false twist to textile rovings the combination of a rotatably mounted member formed with an axially extending aperture, means for rotating the said member, and a false twist member slotted along its length and removably supported within the 45 said rotatable member, one of said members being formed with a recess having at least one bevelled face and the other of said members being formed with a projection which is adapted to enter into the said recess when the twist member is in position within the said rotatable member and to be engaged by the bevelled face of said recess to transmit the rotation of the sleeve member to the twist member, said twist member being 50 freely slidable longitudinally within the said rotatable member whereby upon rotation of the 55 said twist member being impeded it is caused to slide longitudinally under the action of the said bevelled face on the said projection to disengage said projection from the said recess to render inoperative the driving connection between the 60 said rotatable member and the twist member. 65

6. In mechanism for imparting false twist to textile rovings the combination of a rotatably mounted sleeve member, means for rotating the said sleeve member, a twist tube formed with a 70 longitudinal slot and adapted to be inserted into and to be supported by said sleeve member while being slidable longitudinally therein and cooperating means on the sleeve member and on the twist tube for transmitting the rotation of the 75

said member to the said tube so long as the resistance to the rotation of the tube is less than a predetermined value, said cooperating means having mutual engaging surfaces shaped to cause moving apart of the cooperating means when the speed of rotation of the tube is diminished with

respect to the speed of rotation of the sleeve member whereby the tube may be shifted axially by said cooperating means, said tube having means whereby the tube may be slackened in speed or stopped.

FERNANDO CASABLANCAS.
